UNITED STATES PATENT OFFICE.

CHARLES ASHTON HENRY BULLOCK, OF LONDON, ENGLAND.

TYPESETTING APPARATUS.

Application filed May 15, 1926, Serial No. 109,342, and in Great Britain June 25, 1925.

This invention relates to the typesetting apparatus of the kind in which the type is stored in channels, having means by which the bottom piece of type in each channel may be raised above or pushed forward beyond the level of the remaining type in the channel, and may thus be readily abstracted one piece at a time.

In the specification of my previous Patent No. 1,494,215 I have described means by which the last piece of type in any channel, is raised by a separate unit, by the depression of a key. In this case only the one piece of type that it is desired to abstract is raised above the level of the other type in the channel.

My present invention consists broadly in the provision of means for raising or pushing forward the bottom or last piece of type in all the channels at the same time so that for example, in the alphabet A to Z every single letter of the bottom row of type in the apparatus as a whole is raised or pushed forward, and stands in position to be abstracted at once between the finger and thumb, each separate letter standing above or beyond its other similar characters, contained in the channels.

In the accompanying drawings I have illustrated my invention,

Figure 1 being a front elevation of the complete typesetter,

Figure 2 is a side elevational view thereof, and

Figure 3 is a fragmentary view to an enlarged scale illustrating an important detail.

Referring to these drawings the numeral 1 designates the channels in which the types 2 are stacked upon a platform 11 one above the other in the usual manner each channel containing a particular designation of type. At the rear of the machine a sliding plate or plates 3 is or are provided attached to side members 4 upon the ends of each of which a roller 5 is carried. An operating bar 6 carried upon pivoted arms 7 co-operates with all the rollers 5 and the lower end of this bar is connected by a pin 7^a to an operating lever 8 in which is provided a slot 9 for the pin 7^a to slide in. It will be readily seen that by depression of the lever 8 the operating bar is caused to move forward from the position indicated in Figure 2 to the position indicated in Figure 3. In its movement this bar, acting in conjunction with the roller 5 causes the sliding plate 3

which lies normally behind the bottom row of type to be moved forward pushing each designation of type in the lowermost row of types in front of it through an opening in a guide plate 14 to a position from which they can be readily extracted by the thumb and finger. That is to say each of the lowermost types in the various channels is pushed forward through separate holes in a guide plate 14 as indicated in Figures 1 and 3. Upon release of the operating lever 8 the spring 9 returns the bar 6 and its associated elements back to normal position ready for the next operation and it will be understood that the weight of the column of type above it will hold the projected type securely against accidental displacement.

It will be understood that a complete apparatus may be divided up longitudinally of the type channels so as to provide tiers of channels which permits of the use of shorter channels for containing types which are not frequently used and longer channels for types which are in frequent demand.

It will be understood also that although the operating lever 8 is illustrated as a hand lever it can be constructed as a foot lever or a second lever can be attached to it to permit of operation by the foot if desired.

The device as a whole may be erected in any convenient position and for a small size of machine a hinged or pivoted support 12 may be arranged so as to support the frame 13 at a convenient angle for easy manipulation of the type.

The channels 1 may be made in any suitable manner but a simple and convenient method is to divide the interior of the frame 13 up into the necessary number of channels of the desired width by means of strips 14 of wood or other material. It will be clear however, that various modifications of detail and construction may be made within the scope of the appended claims and without departing from the fundamental characteristics of the invention which is the simultaneous moving forward of one of each of all designations of type unless a type of the character is already available for extraction.

Thus the first operation in the use of my invention is to operate the lever 8 by the hand or by the foot, and thus move forward the plate 3 so that all the letters from A to Z will stand clear of their fellows in positions ready for abstraction.

Having abstracted one letter say M the operator will continue to set the other pieces of type until he requires to use another M or other letter of a kind he has already used 5 when he again operates the lever 8 and once again all the vacant positions have type pushed into position ready for abstraction and there is a complete line of type all standing projected ready to be set.

10 What I claim and desire to secure by Letters Patent is:—

1. Typesetting apparatus comprising channels in each of which types of one designation are arranged one above the other, 15 a sliding plate behind the lowest row of types and means for causing this plate to move forward at will and push the lowermost type in each channel to a position of accessibility for extraction, and including a 20 frame subdivided laterally so as to provide tiers of channels one above the other.

2. Typesetting apparatus comprising channels in each of which types of one designation are arranged one above the other, 25 a sliding plate behind the lowest row of types a guide plate in front thereof having separate holes aligned with each of the lowermost types in the row and means for causing said sliding plate to move forward at 30 will and push the lowermost type in each channel through its aligned hole in the front guide plate to a position where each type is accessible for separate extraction by the thumb and finger.

3. Typesetting apparatus comprising channels in each of which types of one designation are arranged one above the other, 40 a sliding plate behind the lowermost row of types, side member attached to said sliding plate, rollers carried at the forward ends of said side members, spring controlled vertical rods engaging with said rollers, means for moving said sliding rods bodily forward to move said sliding plate forward and push the lowermost type in each channel to a position of accessibility for extraction by the thumb and finger.

4. Typesetting apparatus comprising up- 50 right channels, lateral subdivisions in said channels whereby tiers of separate channels are formed, a sliding plate behind the lowermost row of type in each tier each of said sliding plates being common to all the channels in each tier and means common to all 55 the sliding plates for causing said sliding plates to move forward simultaneously at will and push the lowermost type in each channel to a position where each type is accessible for separate extraction by the thumb and finger.

5. Typesetting apparatus comprising channels in each of which types of one designation are arranged one above the other, 65 a sliding plate behind the lowermost row of types, side member attached to said sliding plate, rollers carried at the forward ends of said side members, spring controlled vertical rods engaging with said rollers, means for moving said sliding rods bodily forward to move said sliding plate forward, a guide plate in front of the lowermost row of types having separate holes aligned with each of the lowermost types in the row whereby when the sliding plate moves forward each of the lowermost types is pushed through its aligned hole in the guide plate to a position of accessibility for extraction by the thumb and finger.

6. Typesetting apparatus comprising up- 80 right channels, lateral subdivisions in said channels whereby tiers of separate channels are formed, a sliding plate behind the lowermost row of type in each tier each of said sliding plates being common to all the channels in each tier, perforated guide plates in front of the lowermost types in the channels in each tier the perforations in the guide plates being aligned with the types behind them and means common to all the sliding plates for causing said sliding plates to 90 move forward simultaneously at will and push the lowermost type in each channel through its aligned hole in the appropriate guide plate to a position where each type is accessible for separate extraction by the 95 thumb and finger.

7. Typesetting apparatus comprising channels in each of which types of one designation are arranged one above the other, 100 means operable at will to cause each of the lowermost types to move simultaneously forward to positions for extraction and means to maintain each of the types separated from adjacent types whereby each of said types can be separately extracted by the 105 thumb and finger.

8. Typesetting apparatus comprising a frame means for supporting said frame at an angle, division plates in said frame dividing said frame into channels each adapted to contain types of one designation arranged one above the other, means operable at will to cause each of the lowermost types to move simultaneously forward to positions for extraction and means to maintain each of the 115 types separated from adjacent types whereby each of said types can be separately extracted by the thumb and finger.

In witness whereof I affix my signature.
CHARLES ASHTON HENRY BULLOCK.
